NAVIGATION LOCK CONSTRUCTION

Charles M. Hackett, Nashville, Tenn.

Application November 16, 1935, Serial No. 50,162

7 Claims. (Cl. 61—8)

(Granted under the act of March 3, 1883, as
amended April 30, 1928; 370 O.G. 757)

This invention described herein may be manufactured and used by or for the Government for governmental purposes, without the payment to me of any royalty thereon.

5 This invention relates generally to apparatus for dissipating the energy of falling water, particularly when filling a navigation lock chamber, and includes mechanical and hydraulic principles hereinafter described in the specifications.

10 In the accompanying drawings like characters indicate like parts in the several views that illustrate the invention.

Referring to the drawings:

Fig. 1 is a plan view showing general arrangement of water intake and discharge control valves, stop gates, and dissipating device with its water and air passages arranged for a single lock.

Fig. 2 is a vertical section taken on line 2—2 of Fig. 1.

20 Fig. 3 is a plan view similar to Fig. 1, but illustrating a more compact arrangement of dissipating device and its accessories.

Fig. 4 is a vertical sectional view illustrating the application of dissipating principle to the removal of energy from water falling from greater height than would be required in the filling of a high lift navigation lock.

Fig. 5 is a horizontal section taken on line 7—7 of Fig. 4.

30 The water supply and discharge facilities for navigation locks shown by drawings may be arranged either right or left; also the dissipating device may be used to advantage in a wide range of heads and many combinations. It is also possible, by adding concentric baffling wells and sections of wells around dissipating device with the required number, size, and location of ports and passages through their separating walls, to arrange a series of drops or falls that will be effective in dissipating the energy of water falling from any height, as clearly shown in Figs. 4 and 5 of the drawings.

40 The total port discharge capacity from tube 15 to well 13 is materially greater than that of intake valves 9 and is arranged and proportioned to effectively and safely distribute stress in structure at all stages in the filling of a lock chamber. If level of upper pool is held within prescribed limits, the volume of flow into dissipator does not exceed a predetermined maximum, due to a float actuated stop which limits valve opening in accordance with level of water in pool. The allowed range in pool levels shown by accompanying drawings is 10 feet. This control of flow produces balanced functioning in operation

of dissipator during the time when lock filling is proceeding at a uniformly maximum rate. This period will begin with full open valve 9 and last till backwater from lock chamber begins to cause flooding in chamber 11 at top of dissipator. 5 From this point on the customary slowing down of filling rate will occur. At developments where the upper pool level does not fluctuate more than 3 feet, automatic regulations of inflow are not provided.

10 In the construction for effecting discharge of the water from the lock chamber, valves 24 are provided, and these are similar to the valves used for filling purposes. In fact the valve and gate arrangement in the discharge conduits are similar in construction and operation to those employed for filling the lock chambers. The filling and discharge valves 9 and 24 respectively and their coacting gates are of conventional design and form no part of the present invention except in so far as they provide a suitable valve control for filling and emptying the lock chamber.

15 The discharge valves 24 are grouped with the filling valves 9 and trash racks 28, making it possible to reach any part of valves or accessories with a single small whirler type gantry or stiff leg derrick, thus facilitating rapid repairs, replacement, and inspection.

20 That section of discharge passage 25 in which valve 24 is installed is materially larger than the outer end 26 to reduce water velocity through valve.

25 To avoid undue enlargement of masonry structure which would result in water falling several hundred feet if discharge from wells should all be arranged outward, groups of wells may be superimposed and the lateral movement of water reversed in alternate groups. With this arrangement the reversing well would be a stilling well.

30 Wells only would be used in the groups below the top one.

35 The energy dissipating device, hereinafter referred to as dissipator, covered by this description, consists of a well 13 formed in masonry having water passages 19 and 25 leading from its base and passages for the escape of air 14 leading from its top. The bottom of this well to be at an elevation that insures a sufficient depth of water to provide a stilling pool proportionate to the maximum head of the water falling into it.

40 Inside the well is constructed a metallic or reinforced concrete tube or inverted truncated cone 15 having its outside surface at an angle or vertical and equidistant from the walls of 55

well 13 and at a distance that provides sufficient space to allow free movement of water in all required directions and without causing an appreciable retarding of flow when lock chamber 5 is being emptied.

The inside surface of the tube is stepped or sloped from a smaller size at the bottom to a larger size at the top.

The lower end of the tube rests on the bottom 10 of well and its side walls are pierced by openings or ports, the number, shape, size, and arrangement of which are in accordance with the requirements of the project in which the dissipator is incorporated.

15 The upper end of dissipator consists of a supplemental chamber 11 having an opening in its bottom of the same shape and dimensions as that of the upper end of the tube 15 on which it rests. The wall at one side of the chamber is 20 pierced by an opening 10 for the inflow of water. This opening 10 is divided by one or more partitions 16 so shaped as to create a vortex in flow of water at top of tube. The partition walls 16 also act as supports for roof of 25 inlet opening 10 and have slots at the end nearest control valve 9 for the holding of stop gates 8. An opening 17 for admission of air in ceiling of inlet chamber if desirable may be equipped with mechanically operated shutters and baffles for 30 controlling air supply and blocking spray.

The hydraulic conditions of each project will affect dimensions and mechanical features but the basic principles in design and operation of the dissipator remain constant and can be 35 adapted to any high lift lock.

Water is admitted to chamber 11 at the top of dissipator through valve 9 of a type that insures not only smooth increase and decrease in volume of flow between open and closed position but 40 that will operate with equal smoothness in forward or reverse from any position between full open and closed.

The water falling from supplemental chamber 11 into tube 15 of dissipator entrains air which 45 serves to break up its mass and reduce impact in the stilling pool. With full open intake valves 9 and low water in lock, the considerable head developed in tube 15 forces the air charged water through the lower groups of ports in its wall into 50 the surrounding well 13 where its impact against wall of well 13 breaks the force of jets and releases most of the entrained air which escapes through the vents 14 at top of well 13. The remainder of the entrained air is collected in that 55 section of water passage 19 lying between dissipator well 13 and lock feeder tunnels 20 and is conveyed to the open air through chamber 21, air header 22, and discharged ducts 23 as clearly shown in Figs. 1 and 2 of the drawings.

60 Having described my invention, what I claim as new and wish to secure by Letters Patent is:

1. In a navigation lock construction, the combination with a lock having a lock-filling chamber, the latter being vented to atmosphere at 65 its upper end and connected at its lower end with the lock; of means for introducing water into the chamber adjacent its upper end, means situated central of and co-extensive in length with the depth of the chamber for directing 70 water from the point of introduction to the bottom of the chamber in the form of a column, and means in connection with the last mentioned means and coacting with the surrounding wall of the chamber for entraining air in the falling 75 water to dissipate its energy and for effecting

passage of the water from said centrally located means simultaneously with the release of the greater portion of the entrained air.

2. In a navigation lock construction, the combination with a canal lock and a lock-filling 5 chamber, the latter having its upper end vented to atmosphere and its lower end in communication with valve-controlled, lock-filling and emptying conduits; of means for introducing water into the chamber adjacent its upper end, 10 means situated central of the chamber and co-extensive in length with its depth for directing water from the point of entry to the bottom of the chamber in the form of a descending column of water, inwardly tapered from its upper to its 15 lower end and means in connection with the last mentioned means and coacting with the surrounding wall of the chamber for entraining air in the descending water to dissipate its energy and to effect passage of the water from 20 said centrally situated means to the chamber simultaneously with the release of the greater portion of the entrained air.

3. In a navigation lock construction, the combination with a canal lock and a lock-filling 25 chamber located adjacent the lock, the chamber having its upper end vented to atmosphere and its lower end in communication with valve-controlled, lock-filling and emptying conduits; of a valve-controlled means for introducing water into the chamber at its upper end, means situated central of the chamber and co-extensive in length with its depth for directing the water from the point of entry to the bottom of the chamber in the form of a rotating column of water 30 inwardly tapered from its upper to its lower end and means in connection with the last mentioned means and co-acting with the surrounding wall of the chamber to entrain air in the descending water to dissipate its energy and to 35 discharge the water from the centrally located means to the chamber simultaneously with the release of the greater portion of the entrained air.

4. In a navigation lock construction, the combination with a canal lock and a lock-filling 45 chamber adjacent the lock, the chamber having its upper end vented to atmosphere and its lower end in communication with valve-controlled filling and emptying conduits; of a valve-controlled means for introducing water into the chamber at 50 its upper end, means situated central of the chamber and co-extensive in length with its depth for directing the water from the point of introduction to the bottom of the chamber in the form of a rotating column of water tapered 55 inwardly from its upper to its lower end, means in connection with the last mentioned means and co-acting with the surrounding wall of the chamber to entrain air in the descending water and to effect discharge of the water from said centrally 60 located means to the chamber simultaneously with the release of the greater portion of the entrained air, and additional means located between the filling chamber and the canal lock to release the remaining portion of the entrained 65 air.

5. In a navigation lock construction, the combination with lock passage and a lock-filling chamber, the latter having its upper end vented to atmosphere and its lower end in communication with valve-controlled lock-filling and emptying conduits; of a supplemental chamber situated immediately above the upper end of the filling chamber, valve-controlled means for admitting water to the supplemental chamber, 70

means communicating with the supplemental chamber and extending centrally through the filling chamber to its bottom for discharging the water in the supplemental chamber through the filling chamber in the form of a column inwardly tapered from its upper to its lower end, means in connection with the last mentioned means and co-acting with the surrounding wall of the chamber for entraining air in the descending water to dissipate its energy and to effect discharge of the water from said centrally located means to the chamber simultaneously with the release of the greater portion of the entrained air and additional means located between the filling chamber and the lock to release the remaining portion of the entrained air.

6. In a navigation lock construction, the combination with a canal lock and a lock-filling chamber, the latter having its upper end vented to atmosphere and its lower end in communication with valve-controlled lock-filling and emptying conduits; of a supplemental chamber located centrally of and immediately above the upper end of the filling chamber, valve-controlled means for admitting water into the chamber; means in connection with said valve-controlled means to impart a whirling movement to the water as it enters the supplemental chamber, a cylindrical member communicating at its upper end with the bottom of the supplemental chamber and its lower end resting on the bottom of the filling chamber, means in connection with the

cylindrical member and co-acting with the surrounding wall of the filling chamber to entrain air in the water descending the cylindrical member and to effect discharge of the water from said member simultaneously with the release of 5 the greater portion of the entrained air.

7. In a navigation lock construction, the combination with a canal lock and a lock-filling chamber, the latter having its upper end vented to atmosphere and its lower end in communication with valve-controlled lock-filling and emptying conduits; of a supplemental chamber located centrally of and immediately above the upper end of the filling chamber, valve-controlled means for admitting water into the supplemental chamber, means in connection with said valve-controlled means to impart a whirling movement to the water as it enters the supplemental chamber, a cylindrical member communicating at its upper end with the bottom of supplemental 20 chamber and having its lower end resting on the bottom of the filling chamber, means in connection with the cylindrical member and co-acting with the surrounding wall of the filling chamber to entrain air in the water descending 25 in the cylindrical member and to effect discharge of the water from said member simultaneously with the release of the greater portion of the entrained air, and additional means located between the filling chamber and the lock to release 30 the remaining portion of the entrained air.

CHARLES M. HACKETT.
